United States Patent Office

Des. 233,815

Patented Dec. 3, 1974

233,815

COMBINED SET OF CONDIMENTS JARS AND TRAY THEREFOR

Augusto Salviato, Corso Mario Abbiate, 110,
Vercelli, Italy

Filed June 11, 1973, Ser. No. 369,026

Term of patent 14 years

Int. Cl. D7—06

U.S. Cl. D7—52

FIG. 3

FIG. 4

FIG. 1 is a side elevational view of a combined set of condiment jars and tray therefor showing my new design;

FIG. 2 is a top plan view thereof;

FIG. 3 is a bottom plan view thereof; and

FIG. 4 is an end perspective view thereof.

I claim:

The ornamental design for a combined set of condiment jars and tray therefor, as shown.
